UNITED STATES PATENT OFFICE.

EMIL E. OTTO, OF CHICAGO, ILLINOIS.

GAS-MANTLE AND METHOD OF MAKING THE SAME.

1,146,511.

Specification of Letters Patent. Patented July 13, 1915.

Application filed March 2, 1912. Serial No. 881,187.

To all whom it may concern:

Be it known that I, EMIL E. OTTO, a citizen of the United States, residing at Chicago, in the county of Cook and State of Illinois, have invented a certain new and useful Gas-Mantle and Method of Making the Same, of which the following is a specification.

My invention relates to gas mantles of the inverted type and the same consists in the mantle itself and the method of making the same.

One object of my invention is to produce a mantle of the inverted type which shall be comparatively simple and economical of manufacture and capable of giving the greatest possible amount of light and avoiding the shadow incident to the usual forms or constructions of mantles.

20 A further object of my invention is to provide a simple method or process of producing this gas mantle. Heretofore various ways have been devised to form gas mantles, among which may be mentioned that of gathering and tying the lower end of a knitted tube, and that of cutting and sewing the fabric along curved lines, but these mantles are unsatisfactory, first because of the producing of shadow by reason of the 25 greater amount of material at the lower end, and second because of a lack of uniformity 30 and accuracy in the resulting product.

Speaking in general terms my new method consists, aside from the operation of 35 impregnating with incandescing material and of burning the mantle, in taking a tube of fabric or the like of proper length and diameter, longitudinally infolding one end at least thereof, sewing such infolded end 40 through all the thicknesses and then turning the tube inside out. The resulting mantle has a natural form without the objectionable 45 creasing and bunching incident to other constructions of mantles and the same, moreover, has a smooth rounded bottom which cannot shrink out of shape and which is capable of giving a clear brilliant light 50 through the entire mantle, the major portion of the bottom of the mantle being of a single thickness and of the natural weave of the fabric, that is, without either stretching or bunching. Moreover, absolute accuracy and uniformity of mantle is obtained by my method, and the structure of the mantle is

such that it retains its perfect shape 55 throughout its entire period of use.

In the drawing Figure 1 is a perspective of a mantle of my construction; Fig. 2 is an elevation of two of the knitted tubes in process of manufacture into a mantle; Fig. 3 is an end view on an enlarged scale of one of the knitted tubes; Fig. 4 a sectional plan on the line 4-4 of Fig. 1 but on a larger scale; Fig. 5 a detail section on the line 5-5 of Fig. 4 but on a still larger scale; Fig. 6 an elevation of an instrument or tool employed by me for the purpose of infolding opposite sides of the knitted tube and illustrating a knit tube in position thereon and with its opposite sides so infolded; Fig. 7 a cross section on the line 7-7 of Fig. 6 but on an enlarged scale, and Fig. 8 is a cross section on the line 8-8 of Fig. 6.

In the practice of my invention I cut a knitted tube, of suitable diameter, into the 75 proper lengths as illustrated at 1, 1, in Fig. 2 and in any suitable manner infold the same from opposite sides, such infolded portions being indicated at 1^a in Fig. 3. These infolds extend longitudinally of the tube 80 and while in practice I so infold such tube as to its entire length, it will be understood that it will be sufficient if but one end thereof is thus infolded. After this operation the infolded end of the tube is sewed transversely near the extreme end as shown in Fig. 2 and through the four thicknesses produced by such infolding. The sewing is indicated at 2 in Fig. 2.

The tube is now placed into any suitable 90 light-giving or incandescing solution in the usual and well known manner and is then turned inside out and pulled over the round end of a model and dried thereon. When this tube is thus turned inside out there are 95 formed the two triangular folds indicated at 1^b in Fig. 1, such folds being on the outer surface of the mantle and the apices of such folds meeting at the center of the bottom of the completed mantle, all as clearly shown 100 in Figs. 1 and 4. It will be noted, however, particularly from an inspection of Fig. 4, that nearly all of the bottom of the mantle is of a single thickness and that, moreover, the material or weave of the tube at such 105 bottom portion remains perfect and undistorted and also smooth.

The next step in the method or process is

to remove the mantle from the model and to apply the usual asbestos ring 3 by which the mantle is secured in the usual way onto the ring or holder 4. The mantle is then 5 burned in the usual way whereupon it is ready for use.

In the practice of my invention, in order to facilitate the infolding of the opposite sides of the tube and do this work accurately, I employ the instrument or tool illustrated in Fig. 6. This tool consists of two similar plates 5, 5 with their flat sides parallel to each other and secured together at their lower ends and spaced apart in suitable 15 manner. As shown these plates are spaced apart by means of a plate or block 6 and also by means of two parallel plates 7, one on each side of the block 6. These parts, together with the plates 5, are secured together in suitable manner as by means of 20 the rivets 8. Between the space formed between the two plates 7 are pivoted the lower ends of the two similar arms 9, the pivotal points being indicated at 10. These arms 25 are adapted to swing outwardly to the dotted line position shown in Fig. 6 and to also move inwardly toward each other to a position between the two plates 5, it being understood that these plates are open 30 at their upper ends. By preference these arms are held in their outward dotted line position in suitable manner, as by means of the springs 11, and the movement of these 35 arms is limited by the contact of the inner beveled corners 9^a against the lower extended end of the block 6. The normal position, therefore, of the tool is that indicated in Fig. 6 with respect to the dotted line position of the arms 9. One of the 40 open-ended tubes is now inserted over the two plates 5 and the arms 9 then moved inwardly with the result that the opposite sides of the tube will be accurately and perfectly infolded. The tube is now ready 45 to be sewed in the manner hereinbefore described but in practice I prefer to simultaneously sew a plurality of these infolded tubes at the same time, in the manner indicated in Fig. 2, which shows two of such 50 tubes which have been sewed at the same operation, the same being still connected by the thread. In practice the different tubes are of course cut apart at the proper time for the performance of the remaining 55 steps of the process.

While in practice and by preference, the tube is turned inside out after being impregnated with the incandescing material, it will be understood that the time of these

two operations may be reversed, that is, 60 the tube may be so turned before the impregnating operation.

I claim:

1. The method of manufacturing gas mantles which consists in forming a tube 65 of fabric, infolding an end of the tube longitudinally along opposite sides, sewing said tube transversely at said end to close it, impregnating the fabric with an incandescing material, turning the tube inside out, and 70 burning the mantle.

2. The method of manufacturing gas mantles which consists in forming a seamless tube of fabric, infolding an end thereof along opposite sides, sewing said tube transversely at said end through all the thicknesses, impregnating the fabric with an incandescing material, turning the tube inside 75 out, and burning the same.

3. An inverted mantle comprising a tubular fabric impregnated with incandescing material and formed with an open top and a closed convex bottom, said bottom having a transverse seam and two similar triangular folds, the major portion of such bottom being 80 of single thickness.

4. An inverted mantle comprising a tubular fabric impregnated with incandescing material and formed with open top and closed bottom, said bottom having a transverse seam and two similar triangular folds. 9

5. An inverted mantle comprising a tubular fabric impregnated with incandescing material and formed with open top and closed bottom, said bottom having a transverse seam and two similar triangular folds whose apices substantially meet at the bottom center of the mantle. 95

6. An inverted mantle comprising a tubular fabric impregnated with incandescing material and formed with open top and closed bottom, said bottom having a transverse seam and two similar triangular folds the remainder of the bottom being of single thickness and of the natural weave of the 100 fabric.

7. An inverted mantle comprising a tubular fabric with open top and closed bottom, said bottom being formed by having its opposite sides infolded and sewed transversely and then turned inside out to form a closed bottom having two triangular folds whose apices meet substantially at the bottom center of the mantle. 110
